UNITED STATES PATENT OFFICE.

ASHLEY C. BENNETT, OF MINNEAPOLIS, MINNESOTA.

CARBURETER.

1,136,997.

Specification of Letters Patent.

Patented Apr. 27, 1915.

Application filed February 17, 1913. Serial No. 748,834.

To all whom it may concern:

Be it known that I, ASHLEY C. BENNETT, a citizen of the United States, residing at Minneapolis, in the county of Hennepin and State of Minnesota, have invented certain new and useful Improvements in Carbureters, of which the following is a specification.

My invention relates to carbureters and has for its object particularly to provide a carbureter having means for receiving and breaking up the liquid fuel as the same passes from the feed pipe to the carbureter chamber so that relatively heavy fuel oil 10 may be so subjected to the action of the air and a complete vaporization and mixture with the air will be effected before such mixture leaves the carbureter.

The full objects and advantages of my invention will appear in connection with the detailed description thereof and are particularly pointed out in the claims.

In the drawings, illustrating the application of my invention in one form, Figure 1 is a vertical section taken through the feed pipe of a portion of the carbureter embodying my improvements. Fig. 2 is a fragmentary part sectional view of a detail. Fig. 3 is an enlarged sectional view similar to Fig. 1 showing a different form of feed pipe. Fig. 4 is an elevation partly in section of a slightly modified form of my invention. Fig. 5 is a sectional view of another modification of my invention.

Primarily the invention consists in providing a carbureting chamber 10 formed by the carbureter walls 11 into which projects a feed pipe having connection with a duct 12 leading to a fuel supply reservoir 13 of well known construction, said feed pipe having placed over the same a strainer-like member comprising a series of plates with apertures between the same through which all of the air and all of the fuel must pass, the fuel 40 reaching said plates with the air from the feed pipe and being spread and distributed upon the plates and vaporizing from the same and from the edges of the plates as the current of air passes between said plates and 45 over said edges.

As shown in Fig. 1, the duct 12 leads to a feed pipe 14 which is in the form of a nozzle having a single terminal opening 15 controlled by a needle valve 16, the fuel spray- 50 ing from such nozzle 15 to be acted upon by the devices of my invention.

As shown in Figs. 3, 4 and 5, a feed pipe 17 is employed which is of uniform cylindrical cross section and may be closed at the top or not as desired. The cylindrical feed pipe 60 17 is provided with a series of apertures 18 which are distributed circumferentially about the feed pipe while a needle valve 19 extends centrally through the feed pipe 17 and controls the opening from the duct 12. 65 The duct 12 terminates at the center of a cup 20 located below the mixing chamber 10 and spaced therefrom so as to provide a circumferential opening 21 through which the air passes to a large central opening 70 22 leading into the carbureting chamber 10. Whichever form of feed pipe is employed extends vertically from the center of the cup 20 and centrally through the opening 22 into the mixing chamber 10 to the required 75 height.

As shown in Figs. 1, 2 and 3, a series of annular plates 23 of successively diminishing exterior and interior diameter are laid one upon another, being held slightly spaced 80 from each other by lugs or projections 24 stamped from the body of the plate. These plates in the aggregate form a conical inclosure or strainer surrounding the feed pipe 14 or 17 and are held in position by 85 means of obliquely disposed wires 25 set in the base plate 26 of the carbureter and secured at their top to a top plate 27 to which the feed pipe 17 may also be connected if desired. A similar structure is provided 90 where, as shown in Fig. 4, a ribbon of metal 28 is spun or laid in a spiral with the flat sides adjacent but not in contact, being held positioned by a cap 27 and rods 25 similar to those shown in Figs. 1 and 3. Also, as 95 shown in Fig. 5, a somewhat similar modification of my invention may be effected by winding a steel ribbon in a plain coil but so that the adjacent members of the coil will be slightly spaced. Such a coil may be used 100 flat above a nozzle spraying device such as 15 or may be pushed up in the center, as indicated in Fig. 5, so as to form a conical member surrounding a feed pipe such as the feed pipe 17.

In operation the suction of the air drawing through aperture 22 and passing between the plates forming the strainer will cause the fuel oil to spray out through the nozzle 15 or through the openings 18 in the 110 feed pipe 17. This spray will be carried with the air against the surrounding or

overhanging strainer member and will pass between the plates of such member evaporating from the surfaces thereof and breaking into the smallest particles from the outer edges of said plates over which the air passes at an angle and at the highest velocity. This action will result certainly either in vaporizing or in breaking up the fuel into the finest particles and most desirable form 5 of fuel mixture. The adjacent plate surfaces, whichever form of my invention is employed, will always be so close to one another that the fuel oil must pass between the same in films so that the air having contact 10 with these films and particularly rushing across the edges thereof at the edges of the plates will have the best opportunity to break up the film of oil into extremely fine particles.

20 I claim:

1. A carbureter comprising a carbureting chamber having a central air admission opening, an oil feed pipe extending centrally through said opening and within the carbureting chamber, and an evaporator surrounding said feed pipe and opening through which all air and fuel oil must pass, said evaporator being built up of a multiplicity of juxtaposed parts having their contiguous surfaces widely extended and held just out of contact.
2. A carbureter comprising a carbureting chamber having a central air admission opening, a fuel oil reservoir, and means for conducting oil therefrom and into the carbureting chamber including a feed pipe extending centrally through said opening, a cup-like member surrounding the base of the feed pipe and spaced from the said opening, and an evaporator surrounding said feed pipe and opening through which all air and fuel oil must pass, said evaporator being built up of a multiplicity of juxtaposed parts having their contiguous surfaces widely extended and held just out of contact.
3. A carbureter comprising a carbureting chamber having a central air admission

opening, an evaporator within the carbureting chamber comprising a hollow member 50 closed at the top and having the bottom thereof surrounding the said opening, the walls of said member consisting of a series of parts provided with extended surfaces, the adjacent surfaces being slightly spaced 55 apart, and means for delivering fuel oil within said evaporator.

4. A carbureter comprising a carbureting chamber having a central air admission opening, an evaporator within the carbureting chamber comprising a hollow member 60 and having the bottom thereof surrounding the said opening, the walls of said member consisting of a series of annular plates laid one upon another, and means for delivering 65 fuel oil within the evaporator.

5. A carbureter comprising a carbureting chamber having a central air admission opening, an evaporator within the carbureting chamber comprising a hollow member 70 and having the bottom thereof surrounding the said opening, the walls of said member consisting of a series of annular plates laid one upon another, means for holding the adjacent surfaces of said plates out of contact, and means for delivering fuel oil within 75 the evaporator.

6. A carbureter comprising a carbureting chamber having a central air admission opening, an evaporator within the carbureting chamber comprising a hollow member 80 and having the bottom thereof surrounding the said opening, the walls of said member consisting of a series of annular plates laid one upon another, said plates having the interior and exterior diameters thereof progressively decreasing so that the complete evaporator structure is conical in form, and means for delivering fuel oil within the evaporator.

In testimony whereof I affix my signature in presence of two witnesses.

ASHLEY C. BENNETT.
